UNITED STATES PATENT OFFICE.

CHARLES H. SAPPER, OF SOUTH NORFOLK, VIRGINIA.

SLAT-ADJUSTING DEVICE FOR LOUVER-BLINDS.

1,271,619.

Specification of Letters Patent.

Patented July 9, 1918.

Application filed May 1, 1918. Serial No. 231,980.

To all whom it may concern:

Be it known that I, CHARLES H. SAPPER, a citizen of the United States, and residing at South Norfolk, county of Norfolk, State 5 of Virginia, have invented certain new and useful Improvements in Slat-Adjusting Devices for Louver-Blinds, of which the following is a specification.

The present invention relates to a device 10 for tilting the slats of louver blinds. The objects of the invention are to provide a device which consists of few parts, may be manufactured at a low cost, will hold the slats in any desired position of adjustment 15 without requiring any locking means, will not be deranged or injured by the weather, and to provide a device that is adapted to be attached to the many different constructions of this type of blind. Other objects and 20 features of novelty will be apparent from the description taken in connection with the drawings in which—

Figure 1 is a sectional elevation through the top of a window frame and louver blind 25 showing in elevation an adjusting device constructed in accordance with the present invention applied thereto; and

Fig. 2 is a partial front elevation of the adjusting device and associated parts.

Referring to the drawings it will be seen 30 that the invention is illustrated in connection with a louver blind having a top slat 10 pivoted at its ends, as by means of the pins 11, to the frame 12 for tilting movement about an axis extending longitudinally 35 of the slat. The other slats, one of which is shown at 13, are supported from the top slat 10 in any suitable manner, as by means of the vertical tapes 14 and cross members 15, 40 the slats resting directly on the latter. It is to be understood however that the invention is not limited to any particular construction of louver blind, but is adapted for use with any form thereof.

In the embodiment illustrated, the tilting 45 device comprises a support 16 attached by any suitable means, as the screws 17 to the top of the frame 12. As shown, the support has the spaced depending arms 18 and 50 19 and the threaded rod 20 extends through the arm 18 being rotatably mounted therein and is also rotatably supported in the arm 19 in any suitable manner, as by means of a screw 21. At the front end projecting 55 from the arm 18, the rod has secured thereto

a small sprocket wheel 22 and a chain 23 passes over this wheel and depends at the front of the blind. A housing 24 is arranged around the sprocket wheel so that the chain is prevented from jumping off the 60 wheel, this housing being secured to the arm 18 by means of the ears 25 and screws 26. A nut 27 is fitted to the rod 20 and has an ear or lug 28 at the lower side thereof. A link 29 has one end pivotally connected to 65 this lug and the other end pivotally secured to the top slat 10 at a point eccentric to the axis about which it rocks. Any suitable means may be used for this purpose and as shown the end of the link is formed with 70 an eye 30, which is connected to the top slat by the staple 31.

In the operation of the device it will be seen that movement of the chain 23 will rotate the rod 20, thereby moving the nut or 75 member 27 in a rectilinear path transversely of the top slat of the blind. This movement is transmitted to the top slat by means of the link 29 and tilts the same so that all 80 the slats of the blind may be adjusted to any desired position. As shown in full lines in Fig. 1, the parts are in the positions which they occupy when the blind slats are substantially horizontal. If it is desired to rock or adjust the slats to the dotted line 85 position, then the chain 22 is pulled so as to move the nut or member 27 toward the left as viewed in this figure to the dotted line position, this movement being transmitted by means of the link 29 to the top 90 slat whereby it is tilted.

From the foregoing description it will be seen that the adjusting device is simple and rugged and therefore not easily deranged or injured. Furthermore the construction is 95 such that it may be manufactured at a low cost and can be incorporated in the blind very easily. Moreover it will be observed that the slats will remain in any adjusted position as the nut 27 can be displaced only 100 by movement of the chain 23. Thus the adjusting device positively holds the slats at any angle without any additional locking means.

Although the embodiment illustrated has 105 been described in detail, it is to be understood that the invention is not limited to the specific construction shown, but that changes may be made within the scope of the appended claims.

Having thus described my invention what is claimed as new and desired to be secured by Letters Patent is:

1. The combination with a louver blind 5 having a pivoted top slat, of means for tilting the slats thereof including a threaded member rotatively mounted at the top of the blind, a nut on said member, and a link having one end pivoted to the nut and the 10 other end pivotally connected to the said top slat at a point eccentric to the axis thereof.
2. The combination with a louver blind having a pivoted top slat, of means for tilting the slats thereof including a member 15 mounted to move transversely of the top slat and a link connecting said member and top slat whereby the transverse movement of said member tilts the top slat on its pivots.
3. The combination with a louver blind 20 of means for tilting the slats thereof including a member movable in a rectilinear path transversely of the blind, means for actuating said member, and a link connecting said

member and one of the slats of the blind, whereby movement of said member tilts the 25 said slat.

4. The combination with a louver blind having a pivoted top slat, of means for tilting the slats thereof including, a threaded rod extending transversely of the blind at 30 the top thereof, a wheel secured to the end of said rod, a chain passing over said wheel and depending in front of the blind, a nut fitted on said rod, and a link connecting said nut and top slat.

5. The combination with a louver blind having a pivoted top slat, of means for tilting the slats of the blind including a member movable transversely of the blind, rotative means operable from the front of the 40 blind for moving said member, and a link connecting the member and said top slat, whereby movement of said member tilts the slats.

In testimony whereof I affix my signature. 45
CHARLES H. SAPPER.
